UNITED STATES PATENT OFFICE

104,339

DESIGN FOR A BOTTLE

Irene M. Bocklage, Chicago, Ill., assignor to Cosmesis, Inc., Chicago, Ill., a corporation of Ohio

Application March 25, 1937, Serial No. 68,393

Term of patent 14 years

To all whom it may concern:

Be it known that I, Irene M. Bocklage, a citizen of the United States, residing at Chicago, in the county of Cook and State of Illinois, have invented a new, original, and ornamental Design for a Bottle, of which the following is a specification, reference being had to the accompanying drawing, forming a part thereof. In the drawing—

Figure 1 is a front elevation of a bottle showing
my new design;

Figs. 2 and 3 are side and plan views of the bottle;

Fig. 4 is a section along the line 4—4 in Fig. 1,
looking in the direction of the arrows.

I claim:

The ornamental design for a bottle, as shown.

IRENE M. BOCKLAGE.
